DESIGN FOR WALL-PAPER.

Design No. 12,907, dated April 25, 1882.

UNITED STATES PATENT OFFICE.

EMIL POPCKE, OF NEW YORK, N. Y., ASSIGNOR TO WARREN, FULLER & CO.,
OF SAME PLACE.

DESIGN FOR WALL-PAPER.

SPECIFICATION forming part of Design No. 12,907, dated April 25, 1882.

Application filed February 13, 1882. Term of patent 3½ years.

To all whom it may concern:

Be it known that I, EMIL POPCKE, a citizen of the United States, residing at the city of New York, in the county and State of New York, have invented and produced a new and original Design for Wall-Paper, of which the following specification is a clear description, reference being had to the accompanying photograph, forming part thereof.

- 5 The said photograph represents an elevation of a section of my design for wall-paper. In the photograph the stylobatic bands A and A' respectively form the bottom and top moldings of the wainscoting at the base of the figure, on which the paneling A² is placed in the form of a pedestal. Rising centrally above this pedestal A² is the columnar shaft B, and this is in turn surmounted or capped with the continuous cornice or paneling C c. All of
- 10 this work is richly ornamented with geometrical figures and foliation. The base band or molding A is formed of an upper and lower bordering enriched with geometrical figures, and a central band or paneling enriched with
- 15 diagonal geometrical work and rich clusters of flowers. The upper band, A', of the stylobate is also formed of an upper and lower belt or marginal line richly filled with geometrical figures, and an intermediate band or paneling
- 20 elaborately ornamented with foliage, flowers, and underlying lace bands diagonally arranged.

The paneling of the pedestal is ornamented with a rich floral center-piece surrounded by panel molding of elaborate scroll-work. The side pieces of the pedestal are richly filled with geometrically-formed ornamentation representing "herring-bone work." The cornice c with diagonal open lattice-work, preferably of dark hues on a light background, and the main body or panel C of the said cornice is filled with pointed Gothic arches overtopped and partly hidden by rich floral ornaments. The shaft of the column B is richly filled with foliated and floral decorations. All of these enrichments or ornaments may be painted or printed in any colors desired and on any colored or tinted background desired.

Having described my invention or design, I claim—

The ornamental design for wall-paper or paper-hangings, consisting of the stylobatic bands A and A', with the paneled pedestal figure A² between them, the columnar shaft B, and the cornice or capital figure C c, all enriched with foliation and geometrical figures, substantially as described.

EMIL POPCKE.
